COMBINED CARD DISPLAY AND PENNANT HOLDER

Milan Mudrinich, 33—25 92nd St., Jackson Heights, N.Y.

Filed Feb. 25, 1964, Ser. No. 78,769

Term of patent 7 years

(Cl. D1—3)

FIG. 1

FIG. 2

FIG. 1 is a perspective view of a combined card display and pennant holder showing my new design;

FIG. 2 is a top view thereof.

The broken line showing of the card display member is for illustrative purposes only.

I claim:

The ornamental design for a combined card display and pennant holder, as shown and described.
